UNITED STATES PATENT OFFICE.

WILLIAM C. FEELY, OF NEW YORK, N. Y.

INVALID-BED AND COMMODE ATTACHMENT.

SPECIFICATION forming part of Letters Patent No. 730,010, dated June 2, 1903.

Application filed April 25, 1902. Serial No. 104,653. (No model.)

To all whom it may concern:

Be it known that I, WILLIAM C. FEELY, a citizen of the United States, and a resident of the city of New York, borough of the Bronx, in the county and State of New York, have invented a new and Improved Invalid-Bed and Commode Attachment, of which the following is a full, clear, and exact description.

The purpose of the invention is to provide an invalid-bed made in telescopic sections and means for adjustably and removably supporting a commode beneath the bed in such manner that when the sections of the bed are closed together the commode-support will be under the head-section, enabling the commode to be readily placed upon the support or removed therefrom, and whereby when the sections of the bed are separated the commode will be brought into the space between the bed-sections for direct contact with the body of the patient and in position for convenient use.

Another purpose of the invention is to provide each section of the bed with independent springs and mattresses.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the improved bed with its sections drawn apart and illustrating the commode in position for use. Fig. 2 is a detail longitudinal sectional view illustrating the manner in which one section of the bed is connected with the other. Fig. 3 is a detail view illustrating the manner in which the commode-support has traveling connection with the inner cross-bar of the head-section of the bed. Fig. 4 is a side elevation of the commode. Fig. 5 is a plan view of one section of the bed-springs. Fig. 6 is a plan view of one section of the mattress for the bed, and Fig. 7 is a side elevation of the bed with its sections closed together and illustrating the application of the screw for opening and closing the sections.

The bed is constructed in two sections A and B. The foot-section A consists of side

bars 10, a foot cross-bar 11, an inner cross-bar 12, and a footboard 13, and the head-section B consists of side bars 14, a head cross-bar 15, an inner cross-bar 16, and a headboard 17.

A longitudinal channel 18 is produced in the under face of each side bar 14 of the head-section B, and said channel 18 extends usually from a point near the head end of the said side bars 14 out through the inner cross-bar 16. At the lower portion of the channel 18 a series of transverse rollers 19 is located, as shown in Fig. 2. These channels 18 are adapted to receive horizontal bar extensions 20 from the head ends of the side bars 10 of the foot-section A, and said bar extensions 20 move freely in said channels 18 on said friction-rollers 19. When the sections A and B of the bed are drawn apart, the bar extensions 20 of the foot-section A of the bed are adapted to still remain in the channels 18, but when the sections A and B of the bed are closed the inner cross-bars 12 and 16 are brought close together.

The bedstead is preferably of iron and of that character which is generally used in hospitals and like institutions, the head and foot boards being constructed of side pieces, top and bottom rails, and intermediate upright bars.

The supporting-frame C for the commode D is best shown in Fig. 1, and consists of side bars 21, secured to the inner cross-bar 12 of the foot-section A of the bed, one at each side of the center of said cross-bar, and a connecting cross-bar 22 at the head ends of the side bars 21. The supporting-frame C enters a recess 23 produced in the under edge of the inner cross-bar 16 of the head-section B of the bed, and the side bars 21 of the supporting-frame C rest upon rollers 24, mounted to turn on pins 25, extending from the lower portions of the side walls of the said recess 23, as is shown in Fig. 3.

The commode D is preferably more or less jar-shaped, although it may be given any desired form, and its mouth portion is provided with an inner flange 26, inclined inwardly and downwardly. The mouth-flange of the commode may be cushioned with rubber or other material, if desired. Horizontal lugs 27 extend from the upper edge of the commode D at diametrically opposite sides, and these lugs

27 are adapted to enter recesses in the side bars 21 of the supporting-frame C, and in this manner the commode is held on the supporting-frame. When the sections of the bed are 5 closed together, the commode will be near the head end of the head-section B, enabling it to be readily removed from the said supporting-frame or placed in position thereon. In 10 removing the commode or in placing it in position on the supporting-frame the supporting-lugs 27 are carried to a diagonal position relative to the space inclosed by the frame C.

It may be desirable to adjust the commode upwardly to better suit the position of the 15 patient, and in order that this may be done a series of auxiliary lugs 27^a is located at suitable intervals apart below the upper lugs 27 as is shown in Fig. 4, and any of these auxiliary lugs may be brought to an engagement 20 with the upper face of the supporting-frame, if desired.

The springs E are made in two sections, a section of the springs being fitted to each section A and B of the frame. One section 25 of the springs is illustrated in Fig. 7. These springs are held in position on the sections of the bed, preferably by means of hooks 28, secured to their outer ends, which hooks are adapted to engage with keepers 29, located, 30 respectively, on the foot and head cross-bars 11 and 15 of the bedstead. The mattress is in two sections E' also, one of which is shown in Fig. 8, and said mattress-sections are of the same dimensions as the sections of the 35 springs. The sections of the mattress are preferably held in position on the bedstead by means of loops 30, secured to an edge of the mattress, which loops are brought to an engagement with pins 31 at the outer end 40 portions of the springs, said pins 31 being shown in Fig. 7.

If desired, the foot-section may be supported by intermediate legs 40, the usual legs being provided for the bedstead at the head 45 and at the foot. The intermediate legs 40 when used are provided with casters 41, and casters 42 are likewise connected with the legs of the head and foot sections of the bedstead.

50 In Fig. 7 I have illustrated a means whereby the sections of the bed may be mechanically opened and closed, whereas in Fig. 1 the operation is manually performed. The device for mechanically operating the sections of the bed consists of adjusting-screws G, one of which is located at each side of the bedstead, and each adjusting-screw is provided with a plain or smooth section 43, held to turn loosely in bearings 44, secured, for 55 example, to the foot-section A of the bedstead, and this section of the adjusting-screw is provided with a hand-wheel 45 at its outer end. The threaded sections 46 of the adjusting-screws G are adapted to turn in correspondingly-threaded nuts 47, secured, for example, to the under face of the side bars of 60 the head-section B of the bedstead.

From the above-described construction of bed it is evident that the commode may be brought in position for use without disturbing the patient to any appreciable extent, and that the bedstead after the commode has been used may be restored to its normal position also without material inconvenience to the patient, and that the patient may be 75 supported in a substantially upright position or may remain in a reclining position when the commode is brought in position for use.

Having thus described my invention, I claim as new and desire to secure by Letters 80 Patent—

1. A bedstead constructed in sections held to slide to and from each other, each section having an inner cross-bar at its inner end, the cross-bar of one of said sections being 85 provided with a recess in its under surface, and a commode-support secured to the inner cross-bar of the other section below the level of its upper surface and having a sliding bearing in said recess, as set forth. 90

2. A bedstead constructed in a head and a foot section, each section being provided with a cross-bar at its inner end, one section having channels in its side bars and the other section having extension-rods from its side bars 95 to move in said channels, and a commode-support secured to the inner cross-bar of one section of the bedstead, the opposite end of the said commode-support being passed through a recess in the under face of the inner cross-bar of the opposing section of the bedstead, the said commode-support having a sliding bearing in the said recess, for the purpose set forth.

3. A bedstead consisting of a head and a 105 foot section, each section having an inner cross-bar, the inner cross-bar of the head-section being provided with a recess in its under surface, a supporting-frame for a commode secured to the inner cross-bar of the foot-section, and being passed through the recess in the inner cross-bar of the head-section, channels formed in the under face of the side bars of the head-section, roller-supports in said channels, and bar extensions from the side 110 bars of the foot-section, which enter the said channels and slide on the said roller-supports, 115 as set forth.

4. A bedstead constructed in sections held to slide to and from each other, a commode-support attached to one of said sections and having sliding engagement with the other section of the bedstead, a commode removably carried by said support, and means for adjusting the commode upon the support, 120 as and for the purpose specified.

5. A bedstead constructed in sections held to slide to and from each other, a supporting-frame secured to one of said sections below the level of the upper surface and having 125 sliding engagement with the other section of the bedstead, also below the level of its upper surface, a commode removably carried by the said supporting-frame, the upper surface 130

of the commode being normally flush with the upper surface of the supporting-frame, and means for adjusting the commode upon its support, substantially as described.

5 6. An invalid-bedstead constructed in a head and a foot section, a sliding connection between the two sections, a spring for each section, a mattress for each section, hooks on the springs adapted to engage keepers on the
10 head and foot sections to secure the springs

to the sections of the bedstead and means for securing the mattress-sections to said springs, as described.

In testimony whereof I have signed my name to this specification in the presence of 15 two subscribing witnesses.
